Lawrence J. Fay, Elgin, Ill., assignor to Equipto Electronics Corporation, Naperville, Ill., a corporation of Illinois

Continuation of applications Ser. No. 62,113, Sept. 12, 1960, and Ser. No. 64,453, Mar. 23, 1961. This application Nov. 15, 1961, Ser. No. 67,698

Term of patent 7 years

(Cl. D10—8)

FIG. 1

FIG. 2

FIG. 3

FIG. 4

FIG. 5FIG. 6FIG. 7FIGURE 1 is a front elevation of a door handle, showing my new design;

FIGURE 2 is a side elevation thereof;

FIGURE 3 is a side elevation thereof with the handle pivoted;

FIGURE 4 is a bottom end view thereof;

FIGURE 5 is a perspective view of a modified form of the handle shown in FIG. 1;

FIGURE 6 is a top plan view of the handle; and

FIGURE 7 is a side elevation of the handle.

The dominant features of my design reside in the portions shown in full lines. This application is a continuation of applications Serial Nos. D-62,113 and D-64,453 filed September 12, 1960, and March 23, 1961, respectively, and now abandoned.

I claim:

The ornamental design for a door handle or similar article, as shown and described.
